METALLIC FRAME

Martin Esser, Cleveland, Ohio, assignor to John Harsch Bronze Foundry Co., Cleveland, Ohio, a corporation of Ohio

Application July 21, 1933, Serial No. 681,489

8 Claims. (Cl. 189—75)

This invention relates to window casements and frames of similar architectural form, and more specifically to metal casements embodying structural improvements for effectuating the securement of the frame within the walls of a building subsequent to the erection thereof.

In the erection of brick and stone buildings it has been the practice to lay the masonry to the height of the sills of the door and window casements then set and plumb such frames in position and build the masonry thereabout, or contemporaneous with the erection of the brick and stone work, to lay or build in suitable bonding blocks or anchor plates for the securement of the frames within the walls of the building. Such practice has been found objectionable since it necessitated the delivery of the frames or retaining cleats to the building site in advance of the work of the masons, required meticulous care in setting the casements or laying the masonry and provoked delay and expense in fabricating and allocating the frames and retention plates during the construction of the building.

One of the objects of the present invention, therefore, is to construct a casement frame which will obviate the difficulties defined above and which is formed to facilitate the ready engagement of the frame within the wall of a building after the masonry work has been completed.

Another object of the invention is to construct a frame which is constructed to assure a rigid connection and a tight weather-resisting seal with the contiguous walls of the building when mounted therein.

A further object of the invention is to provide a self contained anchor plate within the casement or similar structural frame which may be readily adjusted to effect the rigid securement of the frame without the arduous labor of cutting and fitting filler blocks or bolting the casement to the sills or lintels embedded within the masonry.

Other objects more or less ancillary of the foregoing and the manner in which all the various objects are realized will appear in the following description which, considered in connection with the accompanying drawing, sets forth the preferred embodiment of the invention.

In the drawing wherein a preferred embodiment of the invention is illustrated—

Figure 1 is an elevational view of a casement frame embodying the present invention.

Figure 2 is an enlarged detail view in section of the casing and a portion of the contiguous wall of the building, the section being shown on a plane indicated by the line 2—2 in Figure 1.

Figure 3 is a transverse sectional view similar to Figure 2, the structure shown herein illustrating the form of rail employed in conjunction with a hinged window sash.

Figure 4 is a detailed view in perspective of the anchor strip or plate for interlocking the frame in the opening formed in the building structure.

As illustrated in Figures 1 and 2 the casement comprises a rectangular frame embodying side rails 10, a transversely disposed top rail 11 and a 10 sill or base member 12. In the structure chosen to illustrate the invention the frame rails are of composite form, each member thereof being constructed of extruded metal members of rectangular cross section. The outer frame rail 13 is 15 formed with inwardly extended flanges 14 which are constructed for interlocking engagement with legs of similar configuration in the inner casing member 15. As shown in Figure 2 the casing 15 constitutes the sash of a window of the permanently affixed type. The frame rail 15, however, may be constructed to form the jamb 15a when employed in connection with a hinged casement or similar structure.

In contemplation of the use of the casement 25 frame embodying the present invention, the masonry 16, during the construction thereof, is laid with a chink or raked joint 17 intermediate the inner and outer courses of masonry and the proportion of the opening formed to admit the 30 frame is slightly larger in length and breadth than the outer dimensions of the casing. The rail 13 is formed with a slot 18 extended throughout the length thereof and of suitable width to receive an anchor plate 19 having an enlarged rib or limit- 35 ing abutment 20 upon the inner marginal edge thereof. The faces of the rib contiguous the plate 19 are beveled inwardly for the reception of ledges 21 formed in the frame 13 adjacent the inner edges of the slot 18. The outer faces of the rib 20 are constituted with a relatively shallow channel groove extended throughout its length. The inner wall of the rail embodies a channel section 22 of suitable width to receive the rib 20 when the plate 19 is in its retracted position in the 45 slot 18. The inner wall of the frame 15 is suitably apertured to receive a plurality of set screws 23 which are threaded in tapped holes in the channel section 22 of the frame 13. The screws 23 are arranged to abut the rib 20 within the 50 channel face thereof and upon adjustment thereof rigidly sustain the plate 19 in its outwardly disposed position in relation to the rail 13.

As illustrated in Figure 3 the inner frame 15a is formed with extended flanges or jambs 24 55

adapted to receive the rails of the hinged casement sash 25. It will be noted that the rail 13 in this structure is identical with the outer rail of the window of the stationary type and it is to be understood that various other structural forms of closure members may be employed with the frame disposed herein without departing from the scope or spirit of the invention.

Preliminary to making an installation of the improved casement frame the grooves 17 in the masonry are first filled with ordinary cement mortar or a suitable caulking or grouting material. The frame is then positioned within the opening in the wall with the plates 18 therein fully retracted within the channel 22. The set screws 23 are then inserted within the apertures in the rail 15 or 15a and drawn down to force the plate 18 outwardly into the groove 17 and into the soft cement mortar embedded in the groove. The chinks remaining between the frame and the masonry may then be caulked or grouted in the usual manner, the securement of the caulking material being aided by the provision of grooves 26 formed in the outer face of the outer rail members. As the beveled faces of the rib 20 are seated upon the ledges 21 the complementary angles of the two engaging surfaces will cause the edges of the rail 13 adjacent the slot to be drawn into intimate engagement with the plate 18 thus effecting the rigid support of the plate within the rail and the rigid anchorage of the frame within the wall.

In addition to its anchoring function, the plate 18 also seals against the entrance of moisture and air or acts as a weather-breaker.

Although the foregoing description is necessarily of a detailed character, in order that the invention may be completely set forth, it is to be understood that the specific terminology is not intended to be restrictive or confining, and that various rearrangements of parts and modifications of structural detail may be resorted to without departing from the scope or spirit of the invention as herein claimed.

I claim:

1. In a frame assembly of the class described, a marginal rail having a longitudinal slot therein, a plate for anchoring the rail to a wall mounted for lateral adjustment within said slot, a rib upon said plate disposed to limit the outward adjustment thereof, and means to lock the plate in its outwardly adjusted position in engagement with the wall of the building in which the door or window is to be installed.

2. In a frame assembly of the class described, a marginal rail having a longitudinal slot therein, an anchor plate mounted for lateral adjustment within said slot, a rib upon said plate disposed to limit the outward adjustment thereof, screws mounted in said rail and engageable with said rib to effect the retention of the plate in its extended position in the wall of the building in which the door or window is to be installed.

3. A frame assembly for use in building construction comprising an outer frame rail and an inner frame rail, the outer rail having a longitudinal slot formed therein, an anchor plate mounted for lateral adjustment in said slot and having a retaining rib formed on the inner edge thereof for limiting outward adjustment of the plate, wedge-shaped ledges extending longitudinally of the rail on opposite sides of said slot and adapted to engage in complementary grooves formed in said rib to effect closure of said slot when said plate is adjusted to its anchored posi-

tion, and adjusting screws extending through said rail and abutting said rib to effect outward adjustment of the plate into anchoring position with relation to the wall of the building in which the assembly is installed.

4. In a frame assembly for use in building construction, a side rail having a longitudinal slot therein, an anchor plate mounted in said slot and movable inwardly and outwardly in relation to said rail, set screws mounted in said rail and having their inner ends arranged to abut the edge of said plate, and means adapted to effect a wedge-sealing engagement of the marginal edges of the slot with the plate when the latter is adjusted outwardly with respect to the rail.

5. In a building structure, a wall having a window or door opening formed with a groove in the marginal edges thereof, a door or window frame assembly having a marginal rail adapted to fit against the wall over said groove, said rail being formed with a longitudinal slot throughout the length thereof, an anchor plate mounted in said slot and adapted to extend into said groove and be embedded in grouting material, said plate being formed with a limiting abutment adapted to contact the rail adjacent said slot, and means adapted to engage said abutment and thrust the plate outwardly and lock the plate in its outwardly adjusted position with respect to said rail.

6. A frame assembly for installing doors, windows and the like in building construction comprising an outer frame rail and an inner casing rail, the outer frame rail having its outer wall formed with a longitudinal slot extending throughout the length thereof, an anchor plate mounted in said slot, the inner wall of said frame rail being formed with longitudinally extending side flanges adapted for inter-locking engagement with said casing rail, and screws passed through said casing rail and threaded through the inner wall of the frame rail into abutting engagement with said anchor plate.

7. A frame assembly for doors and windows for use in building construction comprising an outer frame rail and an inner casing rail, the outer wall of the frame rail being formed with a continuous longitudinally extending groove, an anchor plate adapted to be embedded in grouting material mounted in said groove and formed with a rib on the edge thereof, the outer wall adjacent said groove and said rib being formed with co-acting interlocking wedge portions to effect closure of said groove when the plate is adjusted laterally against said wall, the inner wall of said frame rail being formed with side grooves adapted to receive and retain the edge portions of the casing rail, and a plurality of set screws passed through the inner wall of said frame rail against said rib.

8. In a building structure, a wall having a window or door opening with a groove in the marginal edges thereof, a frame assembly comprising a marginal rail adapted to overlie said groove and having an opening in registration therewith, an anchor member provided with an anchoring portion adapted to project through said opening into said groove and be embedded in soft grouting material, said anchor member being formed with a limiting abutment adapted to contact the rail adjacent said opening, and means adapted to engage said abutment and thrust the anchor member outwardly and lock it in its outwardly thrust position with respect to said rail.
